UNITED STATES PATENT OFFICE

2,043,219

SHOE SEWING MACHINE

Fred Ashworth, Wenham, Mass., assignor to
 United Shoe Machinery Corporation, Paterson,
 N. J., a corporation of New Jersey

Application November 23, 1933, Serial No. 699,341

21 Claims. (Cl. 112—38)

The present invention relates to shoe sewing machines, and is herein disclosed as embodied in a machine for sewing the welt to the sole and out-turned upper of a stitch-down shoe supported 5 on a last.

The present machine is similar in many respects to the stitcher disclosed in the inventor's copending application Serial No. 596,051, filed March 1, 1932 upon which Patent No. 2,015,654 10 issued October 1, 1935, and employs substantially the same operating instrumentalities cooperating in a substantially similar manner to form a lock-stitch seam. These instrumentalities include a rotating shuttle located below the work table, 15 a curved hook needle also located below the work table, a loop spreader for moving the needle loop into the path of the shuttle, a curved awl located above the work table, a looper and a thread arm for placing the needle thread in the needle, a rotary take-up for setting the stitch, and a thread lock against which the stitch is set.

As in the machine illustrated in the application above referred to, the presser foot and work support are mounted on a carriage which is 25 arranged to reciprocate in the line of feed to feed the work, and is advanced by the operation of the stop motion in stopping the machine to carry the work out of the path of the needle, and thus secure an immediate cessation of the sewing 30 as the cam shaft of the machine is brought to a more gradual stop.

In carrying out the present invention, the construction and operation of certain of the operating devices of the machine have been modified 35 and improved, and a number of new features have been added which contribute to produce a more simple and at the same time more effective machine.

More specifically, one feature of the invention 40 relates to the provision of mechanism controlled by the stop motion of the machine to advance the carriage and carry the shoe out of the path of the needle, to release the shoe, and thereafter to return the carriage to its normal operating position ready to receive a new piece of work. Related 45 changes have been made in the mechanisms for controlling the operation of the take-up, the presser foot, and the thread cutting and holding devices, to cause these several mechanisms to perform their accustomed operations, upon stopping the machine, to release the shoe and sever the threads, and at the same time to set these devices in readiness for a new operation on a shoe.

Another feature of the invention consists in 50 the provision of a novel and improved thread

finger comprising two gripping members which are arranged to engage with and form a bight in the needle thread and position one leg of the bight tightly across the looper, and at the same time leave slack thread in the leg of the bight 5 leading to the work to permit the work to be fed at this time without danger of breaking or dislodging the thread.

Another feature of the invention consists in a novel and improved welt cutting device which 10 may be actuated manually during the continued operation of the machine, and which operates instantaneously to cut the welt cleanly and accurately to form a joint with the leading end of the welt. 15

Still another feature of the invention consists in the provision of means for enabling the operator accurately to measure the amount of new welt passed through the welt guide to provide a sufficient length of welt for the beginning of a 20 new sewing operation.

While the several features of the invention are particularly well adapted for use in a machine of the present description, it will be understood that certain features are capable of broader application, and are therefore not to be limited to the exact structure or type of machine herein disclosed. 25

The several features of the invention consist also in the devices, combinations and arrangement of parts herein described and claimed, which together with the advantages to be obtained thereby, will be readily understood by one skilled in the art from the following description taken in connection with the accompanying drawings, in which Fig. 1 is a view in right side elevation of a stitcher embodying the several features of the present invention; Fig. 2 is a view in front elevation of a portion of the head 30 illustrating particularly the instrumentalities for engaging the work, these parts being shown in stop position; Fig. 3 is a view in right side elevation of a portion of the head with parts broken away to illustrate particularly the work supporting carriage, the presser foot mechanism, and the stop motion; Fig. 4 is a detail sectional plan view of mechanism for controlling the presser foot, and is taken on the line 4—4 of Fig. 3; Fig. 5 is a detail view of the presser foot lock taken on the line 5—5 of Fig. 4; Fig. 6 is an enlarged detail view in side elevation of the presser foot clamping and lifting mechanism shown in Fig. 3; Fig. 7 is a sectional view taken on the line 7—7 of Fig. 6; Fig. 8 is a detail sectional view taken on the line 8—8 of Fig. 7; Fig. 9 is a sectional 35

plan view of the machine head taken on the line 9—9 of Fig. 3, the parts being shown in operating position; Fig. 10 is a detail view showing the means for adjusting the feeding movements of 5 the carriage, and is taken on the line 10—10 of Fig. 9; Fig. 11 is a view in rear elevation with the frame broken away on the line 11—11 of Fig. 9 to illustrate particularly the stop motion, the parts being shown in stop position; Fig. 12 is a 10 view of certain of the parts shown in Fig. 11 in running position; Fig. 13 is a view in left side elevation of the head, with portions of the casting broken away to show underlying parts, more 15 particularly the stop motion, the parts being shown in operating position; Fig. 14 is a detail view of the latch for tripping the stop motion into operation taken on the line 14—14 of Fig. 13; Fig. 15 is a detail plan view of the operating cams and the stop motion taken on the line 15—15 20 of Fig. 13; Fig. 16 is a top plan view of the head, illustrating particularly the take-up and thread finger mechanism; Fig. 17 is a detail view in front elevation taken on the line 17—17 of Fig. 16; Fig. 18 is a view in right elevation of the 25 parts as shown in Fig. 17, partly in section to illustrate the underlying parts; Fig. 19 is a detail view partly in section of the thread lock release taken on the line 19—19 of Fig. 18; Fig. 20 is a view in front elevation of the thread finger 30 and actuating mechanism taken on the line 20—20 of Fig. 16; Fig. 21 is a view in side elevation of the parts shown in Fig. 20; Figs. 22 and 23 illustrate successive positions in the formation 35 of the stitch to show particularly the operation of the thread finger; Fig. 24 is a detail view in left side elevation on an enlarged scale, of the needle thread gripping mechanism; Fig. 25 is a sectional view of the parts shown in Fig. 24, on the line 25—25 of Fig. 24; Fig. 26 is a detail 40 sectional view taken on the line 26—26 of Fig. 3, and illustrating particularly the operation of the needle and shuttle thread cutting and holding devices; Fig. 27 is a plan view taken on the line 27—27 of Fig. 26; Fig. 28 is a detail sectional 45 view taken on the line 28—28 of Fig. 27; Fig. 29 is a detail view on an enlarged scale of the welt cutting mechanism looking from the right; Fig. 30 is a plan view of substantially the parts shown in Fig. 29; Fig. 31 is a front elevation of the same 50 mechanism; Fig. 32 is a view similar to Fig. 31 showing the knife in cutting position; Fig. 33 is a detail view partly in section of the welt guide, to illustrate the welt measuring device; Fig. 34 is a detail sectional plan view taken on the same 55 plane as Fig. 9, illustrating particularly the feed carriage and its actuating mechanism; Fig. 35 is a detail view in side elevation of certain of the parts illustrated in Fig. 34; and Fig. 36 is a plan view of the parts illustrated in Fig. 35.

60 As illustrated in the drawings, the machine is driven from a horizontal drive shaft 46 mounted in the base of the machine and connected through a starting and stopping clutch 48 with the armature shaft 50 of an electric motor 52. The drive shaft 46 is connected through bevel gears 54 and 56 with a vertical drive shaft 58 which extends upwardly through the machine column and is arranged to drive the cam shaft 60 through the engagement of a spiral gear 62 on the shaft 58 with a corresponding gear 64 on the cam shaft. The position of the clutch members 48 is controlled by means of a bell-crank clutch shifting lever 66 pivoted at 68 in the base of the machine, and provided with a yoke

with rolls adapted to ride in a groove 70 formed in the sleeve hub of one of the clutch members 48. The other arm of the bell-crank 66 is provided with a bearing surface arranged to engage with an offset portion of a vertically movable link 72 which is connected at its lower end to a horizontal lever arm 73 which carries the starting and stopping foot treadle 74. The treadle arm 73 is pivoted at 76 to the machine frame, and is normally held in a raised inoperative position to 10 disengage the clutch members 48 by means of a tension spring 78 which is connected between the foot treadle and a pin 80 on the machine column. The machine is driven during the operation of stopping the machine at a relatively slow rate as 15 hereinafter more fully described, by means of a constant, slow speed drive which comprises a horizontal drive shaft 82 (see Figs. 1, 9, 11 and 13) mounted in the machine column, and connected through a worm 84 to a corresponding 20 worm gear 86 formed integrally with a slow speed clutch member 88 loosely sleeved to turn on the drive shaft 82. The slow speed drive shaft 82 is driven at a constant rate by means of a belt 90 which passes over a pulley 92 on the end of 25 the slow speed drive shaft 82, and over a corresponding pulley 94 on the constantly rotating armature shaft 50 of the motor 52.

The devices for supporting the work in the machine during the stitching operation, comprise 30 a work support 100 and a presser foot 102 which are mounted, as in the present applicant's pending application above referred to, on a feed carriage 104 (see Figs. 2, 3, 6, 9 and 34) arranged to oscillate about a single pivot to impart the required feeding movements to the work. This pivot comprises a vertically arranged pin 106 secured in a slide 108 which is arranged for forward and retracting movements in the machine frame, and is controlled from the stop motion of the machine to advance the work out of the path of the needle to abruptly terminate the seam when the foot treadle is released by the operator. In accordance with one feature of the present invention, mechanism is provided which acts to advance 35 the carriage and the work supported thereon to inoperative position, to release the work, and thereafter to retract the carriage to its normal operating position as the machine is brought finally to rest. At the same time the speed of 40 the machine is reduced and the cam shaft is driven through the slow speed drive above referred to, to a predetermined stop position with the needle and awl both retracted from the work preparatory for the beginning of a new seam. 45 This arrangement of the operating mechanism enables the sewing operation to be discontinued almost instantaneously while the rotating parts may be more gradually brought to rest in the desired positions to put the machine in complete 50 readiness for the next succeeding stitching operation.

The mechanism by which the carrier 108 is advanced and again retracted in stopping the machine, comprises a cam disk 112 (see Figs. 3, 65 9, 11, 12, 13 and 34) which is secured to a vertical shaft 114 journaled in bearings in the machine frame, and is provided on its under side with a cam groove 116 arranged to receive a roll 118 mounted on the rear end of the carrier 108. 70 In stopping, the shaft 114 and cam disk 112 are rotated through one-sixth of a revolution to advance the carriage and to connect the machine to the low speed drive, and are thereafter driven through another one-sixth of a revolution to re- 75

tract the carriage, disconnect the low speed drive, and bring the cam shaft of the machine to a positive stop in a predetermined angular position. This rotation of the shaft 114 and cam 112 is accomplished by means of a Geneva stop motion, the star wheel 120 of which is secured to the upper end of the shaft 114, and is provided with six slots 122 which are arranged to receive an actuating pin or bolt 124 mounted in the continuously rotating gear 62. During the normal operation of the machine while sewing, the bolt 124 is held in raised position out of engagement with the wheel 120, as shown in Figs. 9 and 14, by the engagement of a latch 126 pivoted on the upper face of the gear 62 with a notch in the bolt. A spring 128 fastened on the upper face of the gear engages with a small pin on the latch to hold it normally in locking engagement with the bolt 124. Upon release of the bolt by the latch 126, the bolt is moved downwardly into operative position to engage in a slot 122 of the wheel 120 by means of a compression spring 130 (see Figs. 9 and 11) carried at its lower end on a pin on the bolt and secured within a recess in the gear 62. The latch 126 is actuated to release the bolt 124, and cause the Geneva wheel 120 and cam disk 112 to be rotated through one-sixth of a revolution to advance or retract the carrier by means of a trip member 132 which is secured to the upper end of a sleeve member 134 (see Figs. 11 and 12), and is arranged when rendered operative to move into the path of and trip the latch. The bolt is returned to raised position where it is again engaged by the latch 126 during the continued rotation of the gear 62 by means of a fixed cam 136 (see Figs. 3, 9 and 11) which is formed on a bracket 138 on the machine frame, and engages an arm 140 projecting laterally from the upper end of the bolt 124. The sleeve member 134 is slidably mounted on a vertical shaft 142 (see Figs. 11 and 12), and is keyed against rotation by the engagement of the pin 144 on the shaft with a slot 146 formed in the lower end of the sleeve. The shaft 142 is mounted at each end in brackets 148 and 150, and is rigidly secured in position by means of a set screw 152 in the bracket 150. A tension spring 154 connected at one end to the set screw 152, and at its other end to a pin on the sleeve member 134, tends to hold the sleeve member in a raised position against the bracket 150 to bring the trip member 132 into the path of the latch 126.

The position of the sleeve member 134 is controlled from the starting and stopping treadle 74 through connections which comprise a plate 156 (see Figs. 11, 12 and 13) mounted to swing about a pivot pin 158 on the machine frame, and provided with a cam slot 160 adapted to receive a cam roll 162 supported on the sleeve member 134. The plate 156 is rotated about its pivot 158 to determine the vertical position of the sleeve 134 by means of a link 164 connected by means of a pin 165 to the plate 156 and at its lower end to a horizontally extending lever arm 166 on a rock shaft 168 (see Figs. 1 and 9). The angular position of the rock shaft 168 is in turn controlled by means of a vertical link 170 which is connected between the lever arm 166 and the foot treadle 74. During the operation on a shoe, with the foot treadle held in its depressed position, the plate 156 is maintained in the operating position shown in Fig. 13, to maintain the sleeve member 134 and trip member 132 in their depressed positions against the pressure of the spring 154 out of the path of the latch 126. When

the foot treadle is released in stopping the machine, the sleeve 134 and trip member 132 are permitted to rise under the influence of their spring 154 to trip the latch 126 and permit the stop motion to be thrown into operation. 5

With the construction and arrangement of the stop motion of the machine herein disclosed, the star wheel 120 and shaft 114 are arranged to be given two 60° turns during two successive revolutions of the main drive shaft 58, the carriage 10 104 being advanced during the first revolution to carry the work out of the path of the needle, and during the second revolution to return the carriage to its normal operating position. Mechanism is also provided which is arranged during 15 the first turn of the star wheel 120 and shaft 114 to engage a slow speed drive to retard and rotate the main drive shaft 58 at a slow rate, and which is rendered operative during the second 60° turn of the shaft 114 to disconnect the slow speed 20 drive and stop the machine in a predetermined angular position with the needle and awl withdrawn from the work preparatory to the sewing of a new seam. These mechanisms are so arranged that the depressing of the starting treadle 25 by the operator to start the machine, will automatically reset the stop motion.

As best shown in Figs. 9, 11 and 13, the slow speed clutch member 88 is arranged to engage with a corresponding conical-shaped clutch 30 member 176 which is keyed to turn with the drive shaft 58. The position of the clutch member 176 lengthwise of the shaft 58 to engage with the slow speed driving clutch member 88, is determined by means of a bell-crank clutch lever 35 178 pivoted at 180 on the machine frame, and provided on one arm with a supporting yoke and two rolls 182 which are arranged to ride in a peripheral groove 184 in the sleeve hub of the clutch member 176. An upwardly extending arm 40 of the bell-crank 178 is provided with a cam roll 186 which is arranged to engage with a peripheral cam surface 188 of the cam disk 112. Two heavy tension springs 190 coiled about the sleeve hub of the bell-crank 178 and having their opposite ends connected respectively to the upwardly extending arm of the bell crank 178 and rigidly secured collars 192 tend to swing the bell-crank 178 in a direction to engage the slow speed driving clutch members 176 and 88, and also to maintain the cam roll 186 in engagement with the peripheral cam surface of the cam disk 112. As clearly indicated in Fig. 15, the first turn of the shaft 114 and cam disk 112 causes the cam roll 186 to ride off the high portion of the cam, permitting the low speed clutch to be engaged, the parts at the end of the first turn having assumed substantially the position shown in Fig. 15. The second 60° turn of the cam 112 causes the roll 186 to be brought again into engagement with 50 the high portion of the cam to move the bell-crank 178 against the pressure of its springs 190 to disengage the low speed clutch members 176 and 88. 55

For bringing the machine to a positive stop in 65 a predetermined position, a latch member 196 is provided which is arranged to engage with a stop member 198 on a disk 200 rigidly secured to the sleeve hub of the low speed clutch member 176 keyed to the drive shaft 58. The latch member 196 is formed on a sleeve member 202 loosely mounted to turn on the shaft 142 immediately below and abutting the sleeve member 134. A second lever arm 204 formed on the sleeve member 202 is provided with a depending cam roll 70 75

206 which is arranged to engage with the peripheral edge of the cam disk 112, and is maintained constantly in engagement therewith by means of a tension spring 208 connected at one end to a pin 210 secured to the sleeve member 202, and at its other end to a pin 212 on the machine frame. The cam disk 112 is provided on its upper peripheral edge, as best shown in Figs. 12, 13 and 15, with three flanges 214 which are arranged 5 to engage against a shoulder 216 on the cam roll 206 to maintain the sleeve member 202 and latch member 196 in a depressed position to hold the latch member 196 out of the path of the stop 198 during a predetermined interval of time during 10 the operation of the stop mechanism. A tension spring 218 connected at one end to the pin 210 on the sleeve member 202, and at its other end to a pin 220 on the machine frame, tends to lift the sleeve member 202 to its raised or 15 operative position to bring the latch member 196 into the path of the stop 198. The operation of this mechanism may be described in connection with the operation of the machine as follows:— With the machine in stopped position, the sleeve 202 has been raised to bring the latch member 196 into engagement with the stop 198, and the cam roll 206 will ride slightly onto the leading end of one of the flanges 214, rotating the sleeve 202 slightly against the pressure of its spring 208, 20 and bringing the latch member 196 to its innermost position against the stop 198. When the starting and stopping treadle is depressed by the operator in starting the machine, the sleeve 134 and the sleeve member 202 abutting therewith are 25 depressed to the position shown in Fig. 9 to disengage the latch 196 from the stop 198, and cause the shoulder 216 of the roll 206 to engage under the leading end of the flange 214, thus locking the sleeve 202 in its depressed position. 30 When the foot treadle is now released to permit an upward movement of the sleeve member 134 and trip member 132 to place the Geneva stop motion in operation, the sleeve 202 and latch 196 are maintained in their low position against 35 the pressure of the spring 218 by the continued engagement of the shoulder 216 of the roll 206 under the flange 214. Each of these flanges is of such length as to maintain the sleeve 202 locked in its depressed position during the first 40 60° turn of the star wheel shaft 114 and cam 112 to advance the carriage and work out of the path of the needle. During the subsequent 60° rotation of the star wheel and the cam 112 to return the carriage to its operating position, and 45 while the machine is being driven by the slow speed drive, the roll 206 passes out from under the rear end of the flange 214, so that the sleeve 202 is permitted to rise under the pressure of its spring 218 to bring the latch 196 into operative 50 engagement with the positive stop 198 to stop the machine. As this position is reached, the roll 206 occupying a raised position, again rides slightly onto the leading end of the flange 214, thus resetting the mechanism for the next 55 cycle of operations.

To hold and position the work, to impart the required feeding movements to the work, and to permit the work to be moved out of the path of the needle at the end of the sewing operation 60 as above described, the work support 42 and presser foot 44 of the present machine are carried on the feed carriage 104. The work support 100 comprises a curved U-shaped member as in the applicant's copending application above referred to, which is rigidly supported on the feed 65

carriage 104 (see Figs. 2, 3 and 9), and has formed therein a rectangular-shaped aperture 224 through which the needle and awl are arranged to operate. As best shown in Fig. 2, the work support is secured at its left hand end to a curved arm 226 on the feed carriage 104, and at its right hand end to a bracket 228 also secured to the carriage 104. 5

The presser foot 102 (see Figs. 2, 3 and 9) is formed on a curved member 230 which is rigidly 10 secured at each end to the two arms of the forked upper end of the presser foot supporting member or bar 232. A rectangularly-shaped aperture 233 is provided in the presser foot 102 to provide a passage of the needle and awl through the 15 presser foot. The presser foot bar 232 is carried on a pair of parallel links 234 pivotally mounted on a supporting post 236 which forms an integral part of the feed carriage 104, so that the presser foot bar 232 is permitted to move in a substantially 20 lengthwise direction to bring the presser foot into and out of clamping engagement with the work. An arm 238 forming an integral part of the lower link 234 and extending downwardly therefrom, is connected to a tension spring 240 which tends to force the presser foot downwardly 25 at all times into engagement with the work.

The presser foot bar 232 is raised to release the work by means of a presser foot lifting lever 242 which carries a roll 244 arranged to engage under the lower end of the presser foot bar 232. With the present construction the presser foot actuating lever 242 forms part of a frame 246 mounted to turn on a pivot shaft 248 on the carrier 108. 35

The presser foot is locked in clamping engagement with the work during each feeding movement by means of a locking wedge construction which comprises a tapered wedge block 249 (see Fig. 3) which is connected by means of a link 250 to move with the presser foot bar 232, and is slidably mounted together with a locking wedge 251 in a wedge box 252. The wedge box comprises two upwardly converging surfaces against which the wedge acts to secure the wedging or 40 locking effect. The locking wedge 251 is arranged when moved downwardly to wedge the two blocks against the two converging surfaces of the wedge box to lock the presser foot in clamping position, and is controlled from the presser foot actuating lever 242 by means of a connecting link 254 secured at one end to the locking wedge 251 and at its other end to the outer end of the presser foot lifting lever 242. A tension spring 256 connected between the presser foot lifting 50 lever 242 and a point on the machine frame, tends to move the lever and the locking wedge 251 connected thereto downwardly to lock the presser foot in engagement with the work. An adjustable stop screw 257 supported on the machine frame is arranged to provide a positive limit to the downward movement of the presser foot lifting lever 242. The upward movement of the presser foot actuating lever 242 during a portion of each sewing cycle, acts through the connecting 55 link 254 to raise the wedge 251 to unlock the presser foot, and through the engagement of the roll 244 with the lower end of the presser foot bar 232, acts to slightly raise the presser foot against the pressure of the spring 240 to permit the back feed movement of the presser foot with 60 relation to the work. The construction and mode of operation of the presser foot locking and lifting mechanism, as thus far described, is substantially that disclosed in the applicant's co- 65 70 75 75

pending application above referred to, to which reference may be had for a more complete illustration and description of this mechanism.

In accordance with one feature of the present

invention, a novel and improved mechanism has been developed for raising the presser foot a uniform distance above the work during each feeding operation regardless of the thickness of the work. This mechanism comprises a cam lever 258 (see Figs. 3, 6 and 9) pivoted at 259 on the machine frame, and provided with two cam rolls 260 offset on each side of the pivot to engage with peripheral cams on the cam shaft, as in the applicant's copending application above referred to. The cam lever 258 is arranged to impart a vertical reciprocatory movement to a lever arm 262 secured to a pivot shaft 264 on the machine frame through a link 266 which is connected at its lower end to the lever 262, and at its upper end to the cam lever 258 by means of a pin and slot connection adjustable to vary the effective throw of the cam lever. The lever arm 262 at its forward end is arranged to bear against a shoe 271 interposed between the end of the lever and a spiral cam 270. The shoe projects from a lever arm 273 (see Fig. 4) loosely pivoted on the shaft 248 and is provided with a roughened surface to cooperate with a correspondingly roughened peripheral surface of the cam 270. The cam 270 is formed on a pivot shaft 272 (see Figs. 4, 6, 7 and 8) supported in bearings in two rearwardly extending arms of the presser foot lifting lever frame 246. The angular position of the spiral cam 270 is automatically adjusted in accordance with the thickness of the work to cause the cam lever 258 and lever arm 262 to impart a uniform lift to the presser foot from the surface of the work. The mechanism for controlling the angular position of the spiral cam 270 comprises a pinion 274 mounted on the shaft 272 to engage with a pinion 276 on a shaft 278 which is supported on the presser foot actuating lever frame 246 parallel to and above the shaft 272. A second pinion 280 on the shaft 278 meshes with a gear segment formed on one arm of a bell-crank lever 282 loosely sleeved to turn on the pivot shaft 248 for the presser foot actuating lever 242 and frame 246. The bell-crank 282 is held yieldingly in a predetermined angular position with relation to the feed carriage 104 by means of a link 284 pivotally secured at one end to the free arm of the bell-crank 282, and at its other end journaled to slide in a bracket 286 formed on the feed carriage 104. A compression spring 288 coiled about the link 284 between a shoulder on the link and the bracket 286 tends to hold the bell-crank yieldingly in a limiting position determined by the engagement of locking nuts 290 threaded on the end of the link 284 with the bracket 286. With this construction and arrangement of the parts, movement of the presser foot lifting lever 242 and frame 246 about the pivot 248 to raise or lower the presser foot bar 238, causes the spiral disk 270 to be correspondingly rotated through the connections above described, with the relatively stationary bell-crank 282 to secure the required adjustment of the angular position of the spiral disk 270.

The operation of this mechanism for lifting the presser foot during each feeding operation may be briefly explained as follows:—With the position shown in Fig. 3, which illustrates the lever 262 in raised position, the shoe 271 resting lightly on the cam 270 and the presser foot 102 in gripping engagement with the work, it will be seen

that the angular position of the presser foot lifting lever 242 and the frame 246 is determined in accordance with the thickness of the work through the positioning of the locking wedge 251 and connecting link 254. The angular position of the frame 246 in turn, acting through the connections above described including the relatively stationary bell-crank 282, causes the angular position of the cam disk 270 to be correspondingly determined to leave a predetermined amount of clearance between the actuating lever 262 and the shoe 271. As the actuating lever 262 is now depressed during the continued rotation of the machine cam shaft, the shoe 271 is brought firmly into engagement with the roughened peripheral surface of the cam 270, locking this member against further rotation with relation thereto, and causing the frame 246 and presser foot lever 242 to be rotated to slightly raise the presser foot 102 from the work. Inasmuch as the disk 270 and the adjusting connections including the pinions 274 and 276, and the gear 280 engaging the segment on the bell-crank 282, are locked against rotational movement during the downward movement of the lever 262 to raise the presser foot, a corresponding rotational movement is imparted to the bell-crank 282 against the pressure of its spring 288. As the lever 262 is again raised to permit the engagement of the presser foot with the work, the spiral cam disk 270 is released from the shoe 271, permitting the bell-crank 282 to return to its normal operating position under the pressure of its spring 288, and causing the angular position of the disk 270 to be again adjusted in accordance with the thickness of the work.

In order to release the work and permit its removal from the machine when the feed carriage 104 is advanced to carry the work out of the path of the needle, mechanism is provided which is rendered operative by the advancing movement of the carriage to raise the presser foot and to lock it in raised position. The locking mechanism provided for this purpose is further arranged to maintain the presser foot in its raised inoperative position during the retracting movement of the carriage, and is actuated to release the presser foot and permit the clamping of a new piece of work in position only upon the depressing of the starting treadle of the machine. For raising the presser foot, an upwardly extending arm 292 is formed integrally with the frame 246, and is arranged during the advancing movement of the carriage to be engaged by a fixed stop 294 on the machine frame, so that the continuing advancing movement of the carriage will act to swing the frame 246 and presser foot lifting lever 242 about the pivot 248 to raise the presser foot to inoperative position. In order to lock the presser foot in its raised inoperative position, a locking mechanism is provided which comprises a latch lever 296 supported on a pivot 298 on the carrier slide 108. The latch 296 is arranged, upon movement of the frame 246 and presser foot lever 242 about their pivot 248 to raise the presser foot to inoperative position, for engagement with a corresponding surface 300 formed on the rear end of a bracket 302 supported on the pivot 248 and held adjustably in fixed position with relation to the presser foot lifting lever 242 and frame 246 by means of a clamping bolt 304 which passes through the lever 242 and a slot 306 in a forwardly extending portion of the bracket 302.

A tension spring 308 connected at one end to the carrier 108 and at its other end to a down-

wardly extending arm 310 of the latch 296, tends to hold the latch in engaging position. The latch is released to permit the movement of the presser foot into operating engagement upon starting the 5 machine through connections controlled by the starting and stopping foot treadle 74 comprising a vertically movable block 312 which is provided with a slot 314 to receive the latch arm 310. A cam 316 formed on one side of the slot is arranged upon downward movement of the block 10 to engage with a corresponding cam 318 formed on the latch arm 310 to trip the latch and permit the return of the presser foot to operating position. For controlling the movement of the block 15 312, a link 320 is connected at its upper end to the block and at its lower end to a laterally extending lever arm 322 rigidly secured to the rock shaft 168 which is in turn controlled by the starting and stopping treadle of the machine as above described. A downward movement of the treadle 20 to start the machine acts through the connections described to depress the block 312, and trip the latch so that the presser foot is permitted to move downwardly into operative engagement 25 with the work.

For raising the presser foot independently of the operation of the stop motion of the machine, a presser foot treadle 324 is provided which is connected by a link 326 to a horizontal arm 328 30 formed in a sleeve 330 loosely mounted to turn on the rock shaft 168. A second arm 332 on the sleeve 330 is connected to impart a corresponding rotational movement to the frame 246 and presser foot lever 242 about the pivot 248 by means of a link 334 connected at one end to the arm 332 35 and at its other end to the frame 246. Lost motion is provided in the connections to permit a free movement of the frame 246 and presser foot lever 242 while the foot treadle 324 is in operative, by means of a pin and slot connection 40 comprising a slot 336 formed in the upper end of the link 334 to engage with a pin 338 on the frame 246. The link 334 also serves as a guide for the block 312, being arranged to pass through 45 an aperture in the block. When the presser foot treadle 324 is depressed, the corresponding downward movement of the intervening connections including the link 334 causes the frame 246 and presser foot lever 242 to swing about their pivot 248 to raise the presser foot from the work. Assuming the machine is in operation, the latch 296 50 is held in a retracted position by the engagement of the cooperating cam surfaces 316 and 318, so that when the presser foot treadle is released, 55 the presser foot is again permitted to return to operative position. If, on the other hand, the presser foot treadle is depressed to raise the presser foot with the machine in stop position, the presser foot will be latched in its raised position 60 by the engagement of the latch 296 with the corresponding member 300 secured to the frame 246.

As in the inventor's copending application above referred to, the feed carriage 104 is arranged to swing about its pivot in timed relation to the operation of the thread handling devices and the intermittent clamping movements of the presser foot to feed the work. With the present construction, a novel and improved construction 65 is provided for imparting these feeding movements to the feed carriage 104 which comprises a frame 340 arranged to oscillate about a fixed pivot 342, and provided at its upper end with a cam lever arm 344 on which is carried a roll 346 70 to engage in a cam groove 348 which is formed

in the lower face of a cam cylinder 350 mounted on the vertical drive shaft 58. There is also supported on the frame 340 directly beneath the pivot 342, a rearwardly extending guideway or track 352 which is located in a substantially parallel relationship to a corresponding track or guideway 354 formed on a rearwardly extending bar 356 fixedly mounted on the feed carriage 104. Oscillatory movements are imparted to the bar 356 and feed carriage 104 from the continuously oscillating frame 340 and track 352 through an adjustable connection which comprises a block 358 slidably mounted in the track 354, and a block 360 secured to block 358 by a pin 362 and arranged to ride in the track 352. 10 It will readily be seen that a movement of the blocks 360 and 358 toward or away from the axis of oscillation provided by the pivot shaft 342 will result in correspondingly decreasing or increasing the scope of the oscillatory movements to 20 decrease or increase the length of stitch produced. An adjustment of the position of the blocks 358 and 360 to determine the length of stitch may be conveniently made by the operator through connections which comprise a link 25 364 formed on the block 358 and connected at its forward end to a lever 366 supported intermediate its length on a pivot 368. The position of the lever 366 is in turn determined by means of a rack 380 which meshes with a corresponding gear segment 382 formed on the free end of the lever 366. The rack 380 is mounted to slide in a guideway 384, being held frictionally in position by cover plates 386. A control handle 388 is provided to permit the operator conveniently to 30 shift the rack and connections controlled thereby to secure the required length of feeding movement. In order to permit the operator readily to set the rack in either of two limiting positions to provide a long stitch of predetermined 40 length required on the side portions of the shoe margin, and a relatively short stitch around the toe, a plate 390 is adjustably secured to the rack 380 by means of a clamping bolt 392 journaled through the plate and through a slot 394 in the 45 rack 380, and is arranged to cooperate with two corresponding stop members 396 and 398 supported on the machine frame. In order to permit a variation in the amount of the adjustment 50 which may be obtained in the length of feed, the stop member 398 is adjustably clamped in position by means of a clamping nut 400 which extends through a slot 402 in the stop member 398.

The thread handling devices of the present 55 machine, as best shown in Figs. 1, 2, and 16 to 23 inclusive, of the drawings, include a curved hook needle 404, an awl 406, a looper 408 for placing the thread in the hook of the needle, a thread finger comprising the gripping members 410 and 412, a shuttle 414, a loop spreader 416, and a take-up 418.

The shuttle 414, located beneath the work support as generally indicated in Figs. 2 and 13 of the drawings, is of the rotary type, and comprises a shuttle casing formed of a gear 420 having its center portion cut away to receive the bobbin or cop casing 422, and two plates 424 and 426 which are screwed to opposite faces of the gear and project beyond the ends of the gear teeth to form a track which is engaged by correspondingly-shaped supporting and guiding tongues formed on supporting brackets 428. The shuttle is driven by means of a gear 430 arranged to mesh with the gear member 420, and 75

secured to one end of a drive shaft 432 which carries at its other end a spiral gear 434 arranged to engage with the spiral gear 64 on the main cam shaft 60. The loop of needle thread 5 is taken in the shuttle hook 436, and is held in position between adjacent teeth of the gear 420 as the loop is carried around the shuttle.

The loop spreader 416 as generally indicated in Figs. 2 and 3, is supported on a shaft 438 which is rocked during each cycle of operations to move the loop spreader and needle loop engaged thereby across the path of the shuttle hook 436. The looper 408, as shown in Fig. 2, is provided with a passageway through which the thread is drawn from the supply, and a notched portion 439 across which the thread is laid by the thread finger to position the thread in the path of the needle hook. Inasmuch as the shuttle, loop spreader and looper, together with their actuating mechanism have substantially the same construction and mode of operation as the corresponding elements more fully set forth in the applicant's copending application Serial No. 596,051 above referred to, further illustration or description of these parts is believed unnecessary.

With the present construction, a novel and improved thread finger is provided which is constructed and arranged to position the thread in the looper in the path of the needle hook with certainty, and without injury to the thread which might arise either from excessive reaving of the thread through the thread handling mechanism, or from unnecessary strains placed on the thread during the forming of the stitch. To this end the two members 410 and 412 are arranged to positively grip the thread in the position shown in Fig. 20, and then to lay the thread tightly across the two arms of the looper in the path of the needle, while at the same time leaving a certain amount of slack thread in the lower leg of the bight thus formed to permit the thread extending from the last formed stitch to be laid along the work by the movement of the presser foot with relation thereto preparatory to feeding the work as the needle is again withdrawn to take up a new loop. The mechanism for imparting the required gripping and positioning movements to the members 410 and 412 of the thread finger is similar in many respects to that illustrated in the applicant's copending application above referred to, but may be briefly described as follows in connection with Figs. 2, 16, 20 and 21 of the drawings.

The member 410 is formed in the lower end of a post 440 which is journalled to rotate within a sleeve member 442 which carries at its lower end the cooperating gripping member 412. The sleeve is in turn mounted for lengthwise sliding movements within a bracket 444 supported on a pivot shaft 446 on the machine frame. The relative angular positions of the post 440 and sleeve 442 are controlled by means of a vertically extending plate 447 which has formed therein a cam slot 448 arranged to receive a follower 450 secured to the upper end of the post 440. A forked member 452 formed on the upper end of the sleeve 442 engages with the sides of the plate 446 to prevent rotational movements of the sleeve 442 and the member 412. Vertical sliding movements are imparted to the sleeve 442 and post 440 with relation to the bracket 444 through connections which comprise a link 454 connected at one end to the sleeve 442, and at its other end to a lever arm 456 mounted on a sleeve hub or frame 458 on a pivot shaft 460. There is also se-

cured to the frame a cam lever arm 462 which carries a roll 464 arranged to engage in a cam groove in the periphery of the cam cylinder 350. The vertical movements thus imparted to the sleeve 442 and post 440 cause a relative rotational movement to take place between the post 440 and sleeve 442 to move the members of the thread finger into and out of gripping engagement through the action of the cam slot 448 and follower 450. Rotational movements are also imparted to the pivot shaft 446 and bracket 444 secured thereto to impart the required lateral movements to the thread finger to stretch the thread across the looper by means of connections which comprise a lever arm 466 secured to the rock shaft 446, and connected by means of a link 468 to one arm of a cam lever 470 which is pivotally mounted at 472 on the machine frame, and at its other end carries a roll 474 which engages with a cam groove formed in the upper face of the cam cylinder 350.

The thread take-up as illustrated in Figs. 1, 16, 17 and 18, comprises a cylindrical casing 480 within which is housed a take-up roll 482 supported on an arm 484 secured to turn with a constantly rotating shaft 486. A disk 488 supported on the end of the shaft 486 provides a shield to insure the engagement of the thread with the take-up roll 482 between the disk 488 and the adjacent wall 499 of the casing 480. The shaft 486 is constantly driven from the vertical drive shaft 58 through connections which comprise a shaft 492 located parallel to and to the rear of the shaft 486, and having mounted thereon a spiral gear 494 which meshes with a corresponding spiral gear 496 on the drive shaft 58. At its forward end the shaft 492 is provided with a counterbalanced arm 500 which is connected through a link 502 to a disk 504 on the adjacent end of the shaft 486, so that the take-up roll 482 is driven at a constantly varying rate.

As best shown in Figs. 1, 2 and 17, the thread is drawn from the usual wax pot 506 through a thread lock 508 around an idler roll 510 over the take-up roll 482 and around a thread tension roll 512, and thence to the looper 408. The thread lock as shown in Fig. 18, comprises a bearing surface designated at 508, and a cooperating plunger 514 which is forced in a direction to grip the thread between the surface 508 and the end 516 of the plunger by means of a compression spring 518. The plunger is moved against the pressure of its spring during a portion of each sewing cycle to permit thread to be drawn off from the supply by means of a lever 520 connected at one end to the plunger and at its other end provided with a cam roll 522 arranged to ride against a cam surface formed on one face of the disk 504.

The take-up and its actuating mechanism as thus far described are substantially the same as the corresponding mechanisms illustrated and described in the applicant's copending application above referred to. Mechanism is also provided as in the application above referred to, which cooperates with the stop motion of the machine to render the take-up inoperative to pull in the needle loop and prevent the severed end of the needle thread from being pulled out of the gripper by the continued rotation of the take-up after the threads have been severed from the work in stopping the machine. With the present construction this mechanism is rendered operative to disengage the thread lock by the advancing movement of the feed carriage 104, and acts to maintain the thread lock out of oper-

ation during the continued rotation of the drive shaft 58 and of the take-up while the feed carriage is being returned to its normal operating position preparatory to starting a new seam. A 5 trip mechanism is arranged to operate automatically in starting the machine to release the thread lock and permit the normal operation of the take-up.

The mechanism for disengaging the thread lock in stopping the machine comprises a lever arm 526 (see Fig. 16) which is secured to the vertical rock shaft 368 and projects into the path of a stop 530 on the carrier slide 108. A second arm 532 on the rock shaft 368 engages the end 10 of a spring-pressed plunger 534 which in turn 15 engages with one arm of a lever 536 pivoted at 538 on the machine frame, the other arm of said lever being arranged to engage with a nub 540 on the thread lock actuating lever 520. The advancing movement of the carrier slide 108 and feed carriage 104 causes the stop 530 to engage 20 with the lever arm 526 to rock the shaft 368, and through the connections described to retract the plunger 514 against the pressure of its spring 25 516 to disengage the thread lock. In order to maintain the thread lock in its open position as the feed carriage 104 and slide 108 are again retracted to their normal operating position, a latch lever 542 (see Figs. 17, 18 and 19) is pivoted 30 at 544 on the take-up casing 480, and is arranged to engage in the notch 546 formed in the plunger 514. A spring 548 coiled about the pivot 544 tends to force the latch lever 542 yieldingly into 35 engagement with the notch. A second arm of the lever 542 carries a roll 550 which is arranged to engage with a cooperating nub 552 on the take-up arm 484 to trip the latch in starting the machine.

The operation of the take-up and the release 40 for the thread lock in starting and stopping the machine is as follows:—When the stop motion in the machine is thrown into operation, the advancing movement of the slide 108 and feed carriage 104 acts through the connections above de- 45 scribed including the lever 536 to retract the thread lock plunger 514 simultaneously with the cutting of the partially drawn in loop of needle thread beneath the work and the gripping of the severed end, so that additional thread can be 50 drawn off from the supply to take the place of that ordinarily taken up from the needle loop as the take-up roll 418 continues to move upwardly to its stitch tightening position. The latch lever 542 now operates to latch the plunger 514 in its 55 retracted position. During the subsequent rotation of the main cam shaft of the machine to stop position, the take-up roll will move through another complete revolution, being finally brought to rest in the low position illustrated in Fig. 17. During this revolution of the take-up, the trip 60 552 moving therewith engages with the roll 550 to raise the latch 542, but is inoperative to release the thread lock plunger 514 which is maintained in its retracted position at this time by the actuating lever 536. The retracting move- 65 ment of the feed carriage as the machine finally comes to rest, takes place at a point in the cycle after the trip 552 has passed the roll 550, so that the thread lock is maintained in its open position 70 as the machine comes to a stop. When the machine is again put in operation, the initial upward movement of the take-up roll 418 which ordinarily operates to pull in the needle loop from the shuttle and to set the stitch, again operates to draw in any new thread which may be

needed from the supply through the open thread lock, so that the end of the thread may be retained by the gripper for the starting of a new seam. As the take-up roll 418 reaches the dot-and-dash line position shown in Fig. 17, the roll 550 is engaged by the trip 552 to move the latch 542 out of engagement with the plunger 514 to permit the thread lock again to close. During the subsequent operation of the machine, the thread lock will operate in its normal manner, 10 remaining closed during the major portion of each cycle of operation to permit the drawing in and setting of the stitch against the thread lock.

With the present construction, thread cutting and gripping devices are provided which are rendered operative during the advancing movement of the feed carriage 104 to sever the needle and shuttle threads beneath the work and to grip the severed ends preparatory for the beginning of a new seam. These devices include a thread cutting knife 556 formed on one end of an arcuate-shaped member 558 arranged to slide in an arcuate guideway provided in one of the supporting brackets 560 for the work support. Formed integrally with the knife is a guiding member 562 15 which extends beneath and somewhat in advance of the knife blade and is arranged, during the advancing movement of the knife, to engage with and force the shuttle thread against a spring clip 564, so that the severed end of the thread 20 will be held between the clip and an adjacent portion of the work support. The knife is advanced during the advancing movement of the work support to sever the needle and shuttle threads and to grip the severed end of the shuttle 25 thread, through connections which comprise the bell-crank lever 566 pivoted at 568 on the feed carriage 104, and connected at one end by a ball and socket joint to the knife slide 558, and having 30 its other end arranged to engage in a socket 570 formed in a stationary bracket 572 of the machine.

In accordance with one feature of the present invention, a novel and improved means is provided for gripping and holding the severed end 45 of the shuttle thread and for severing the needle thread in such a manner that there will be no danger of sewing the short loop cut from the needle thread or the loose end of the shuttle 50 thread into the new seam at the beginning of a new shoe sewing operation. To this end the spring clip 564 consists of a wire spring which is secured to a post 574, is bent into a position 55 extending at right angles to the path of movement of the thread cutting knife, extends forwardly to a position adjacent the cutting position of the knife, thence laterally at right angles to the direction of movement of the knife, and again forwardly to a position below the path of the advancing guide member 562. It will readily be seen from an inspection of Fig. 26, that the advancing movement of the knife 556 and guide member 562 will cause the guide member to engage and depress the spring member 564, and will 60 force the threads, extending beneath the work, between the under side of the presser foot and the spring clip when they are severed by the knife. As the knife is now retracted through the operation of the bell-crank 566 upon the retracting 65 movement of the carriage, the severed loop of needle thread and the entire end of the shuttle thread will extend beyond the engaging surface of the spring member 564 as indicated in Fig. 28, so that the severed portions of the needle thread 70 may be permitted to drop out of the machine, 75

and the severed end of the shuttle thread will be held entirely behind the spring.

There is also provided with the present construction a needle thread gripping and holding device which comprises a curved member 576 mounted in a corresponding guideway in the presser foot 102, and provided at its forward end with an offset nib 578 which is arranged upon movement of the member 576 to engage with and grip the needle thread between adjacent gripping surfaces 580 formed in the presser foot. As best shown in Figs. 2, 3, 24 and 25 of the drawings, mechanism is provided for controlling the operation of the gripper member 576 which acts during the advancing movement of the feed carriage 104 to cause said member to grip the thread, and thereafter maintains said member in gripping position during the retracting movement of the carriage to operative position, and until the beginning of a new seam. This mechanism comprises a compound lever made up of a lever arm 592 pivoted at its lower end at 584 on the machine frame and provided adjacent its upper end with a pivot pin 586 on which is mounted a frame 588. An upwardly extending arm 590 formed on the frame 588 is provided with an arcuate guideway 600 arranged to receive a pin 602 secured to the rear end of the needle thread gripping member 576. The lever arms 582 and 590 are held yielding in fixed relationship to each other to move about the pivot 584 as a single unit by means of a heavy compression spring 604 which is inserted between a recess 606 on the machine frame and a downwardly extending arm 608 formed on the frame 588. To assist in maintaining this relationship between the parts, a lighter tension spring 610 is coiled within the spring 604, and is secured at one end to a pin 612 secured to the machine frame, and at its other end to a pin 614 secured to the lever arm 582. During the advancing movement of the feed carriage 104 in stopping the machine, the compound lever comprising the arms 582 and 590 is held in a relatively retracted position against the pressure of the heavy spring 604 by the engagement of a portion of the frame 588 with a corresponding detent 616 formed on a bracket 618 on the machine frame, so that a relative retracting movement of the gripper member 576 takes place to cause the offset nib 578 to engage with and grip the needle thread between the adjacent gripping surfaces 580 on the presser foot. Due to the compound construction of the control lever which permits the frame 588 and lever arm 590 to swing about its pivot 586 against the pressure of the heavy spring 604, a yielding gripping engagement of the needle thread is secured without the necessity of a fine adjustment in the positioning of these parts. In order to maintain a gripping engagement of the needle thread during the retracting movement of the feed carriage 104 to starting position, a latch member 620 is mounted to turn on the pivot 586, and is arranged upon forward movement of the carriage 104 to drop behind an abutment 622 on the work supporting bracket 226, so that on the return movement of the carriage, the compound lever 582, 590 is moved positively with the feed carriage against the pressure of the heavy spring 604 to maintain a tight clamping engagement of the gripping member 576 with the needle thread. The latch member 620 is actuated by means of a small tension spring 624 connected at one end to the latch lever 620, and at its other end to the lever

arm 582. In starting the machine the latch 620 is caused to turn about its pivot against the pressure of the spring 624 to disengage the latch from the abutment 622, and permit the advance of the compound lever 582, 590 under the pressure of the spring 604 to release the needle thread by means of a cam actuated lever 626 pivoted at 628 on the machine frame, and provided with a forwardly extending arm arranged to overlie a corresponding projection formed on the rear end of the latch 620 with the compound lever 582, 590 in the retracted position shown in Fig. 24. At its rear end the cam lever 626 is arranged to engage with a cam 630 formed on one end of the cam shaft 628, and is held yieldingly in engagement therewith by a tension spring 632 secured at one end to the cam lever, and at its other end to a pin 634 on the machine frame.

In carrying out certain features of the present invention, a novel and improved welt guiding and severing device is provided under the control of the operator, which has a substantially instantaneous action to sever the welt when rendered operative, and thus enables the operator to sever the welt during the continued operation of the machine at the exact point desired to secure an accurate joint with the leading end of the welt. As best shown in Figs. 1, 2, and 29 to 33 inclusive of the drawings, the welt is fed from the usual reel 636 through a welt guide 638, secured to the presser foot bracket, to the point of operation on the work. The welt cutting mechanism comprises a cutter member 640 which is mounted to slide in a slot 642 formed in part in a bracket 644 integral with the member 230 which carries the presser foot 102, and is arranged to intersect the guideway 638 for the welt at an angle to form a bevelled end to the welt. A cover plate 646 screwed to the bracket 644, serves to complete the slot 642 and at its lower end supports the welt guideway 638. At its upper end the cutter member 640 is provided with an offset portion arranged to engage in a slot formed in the end of a lever arm 648 mounted to turn on a short rock shaft 650 which is journalled in a bearing formed in the right hand fork of the presser foot bar 232 as viewed from the front of the machine. There is also mounted to turn on the rock shaft 650 a second lever arm 652 which is adjustably connected to move with the cutter actuating lever 648 by means of a clamping screw 654 screw-threaded in the lever arm 648 and arranged to extend through a slot 656 in the lever arm 652. A heavy spring 658 coiled about the bearing for the rock shaft 650 and engaging at one end with the lever arm 652, tends at all times to depress the lever arm 652 and the cutter actuating lever 648 secured thereto, to sever the welt. The levers 652 and 648 are normally held in raised position against the pressure of the spring 658 by means of a toggle connection comprising a link 660 which is punched to receive the tapered end of the arm 652, and a link 662 pivotally connected to the link 660, and at its lower end to the presser foot bar 232. The toggle links 660 and 662 are normally locked in straightened position slightly to the right of the line of centers as shown in Fig. 31, by the engagement of adjacent surfaces 664 formed respectively on the toggle links 660 and 662, the links normally being held in this position by means of a small spring 666 connected at one end to the presser foot bar 232, and at its other end to the toggle link 662. With this construction and arrangement of the parts, it will

readily be seen that the braking of the toggle joint will cause the levers 648 and 652 to be instantaneously depressed by the action of the spring 658 to drive the knife downwardly to sever the welt. A manually operated lever or trip 668 secured to the toggle link 660, provides a convenient means for enabling the operator quickly and efficiently to break the toggle and sever the welt.

With the present construction, mechanism is also provided which is rendered operative by the return movement of the feed carriage 104 to operating position in stopping the machine to straighten the toggle and reset the welt cutting mechanism preparatory for the starting of a new sewing operation. For this purpose a downwardly extending lever arm 670 is secured to the rock shaft 650, and is arranged for engagement with an actuating lever 672 pivoted at 674 on the machine frame. The lever 672 has secured thereto intermediate its length a bracket 676 with an offset portion arranged to engage in front of the pivot shaft 568 on the feed carriage. A tension spring 678 secured at one end to the lever 672 and at its other end to a pin 680 on the machine frame, tends to hold the lever arm 672 and bracket 676 at all times in engagement with the shaft 568. In the operation of the machine, the welt cutting mechanism is tripped by the operator to sever the welt, the sewing is continued across the abutting ends of the welt to finish the seam, and the stop motion is then thrown into operation to advance the feed carriage 104 to carry the work out of the path of the needle. This advancing movement of the carriage causes the lever 672 to be advanced with the feed carriage 104 through the engagement of the bracket 676 with the shaft 568 to engage and move the lever arm 670 about its pivot to raise the lever arms 648 and 652 and reset the toggle.

Before the commencing of a new seam, it is necessary to advance the severed end of the welt through the guideway 638 to position the leading end of the welt in the path of the needle. With the present construction, a device is provided to enable the operator to conveniently and accurately advance the leading end of the welt to the exact position required for the starting of a new seam. As shown particularly in Fig. 33, this mechanism comprises a tube 682 mounted for a limited sliding movement on the welt guide 638, and in its rear position extending a predetermined distance beyond the end of the welt guide 638. The movement of the tube 682 on the welt guide 638 in each direction is limited by the engagement of a projection 684 on the forward end of the tube with the corresponding slot 686 in the guideway 638. A tension spring 688 connected at one end to the tube, and at its other end to the machine frame, tends to hold the tube normally in a fully extended position. When it is desired to feed the additional welt through the welt guide preparatory to starting a new seam, the operator grasps simultaneously the rear end of the tube and the welt, and advances the tube and the welt to the forward limit of movement of the tube, as shown in the dotted line position in Fig. 33, thus causing the welt to be advanced a predetermined distance to place the leading end of the welt exactly in the position required. Upon releasing the tube and the welt, the tube will return to its normal full line position as shown in Fig. 33 under the pressure of its spring 688.

The welt severing mechanism herein disclosed forms a portion of the subject-matter of application Serial No. 747,536 filed October 9, 1934.

The invention having been described, what is claimed is:

1. A sewing machine having, in combination, stitch forming devices including a needle, work supporting devices for positioning the work in the machine, and means rendered operative upon stopping the machine for actuating said work supporting devices to move the work out of the path of the needle and to release the work, and thereafter to position said work supporting devices to receive new work in sewing position. 5

2. A sewing machine having, in combination, stitch forming devices including a needle, work supporting devices to position the work in the machine, and means acting upon said work supporting devices during the continued operation of the stitch forming devices to move the work 10 out of the path of the needle and to release the work, and thereafter to position said work supporting devices to receive new work in sewing position. 15

3. A sewing machine having, in combination, stitch forming devices including a needle, clamping devices for supporting the work in the machine, and means rendered operative upon stopping the machine for actuating said clamping devices to move the work out of the path of the needle, and thereafter to position said clamping devices to receive new work in sewing position. 20 25

4. A sewing machine having, in combination, stitch forming devices including a needle, work supporting devices including a work support and a presser foot, a carriage on which said work support and presser foot are mounted, and means rendered operative upon stopping the machine for actuating said carriage to move the work 30 out of the path of the needle and to release the work, and thereafter to return the carriage to operating position. 35 40

5. A sewing machine having, in combination, stitch forming devices including a needle, work supporting devices including a work support and a presser foot, a carriage on which said work support and presser foot are mounted, means acting normally to hold the presser foot and work support in clamping engagement with the work, 45 and means rendered operative upon stopping the machine for actuating said carriage to move the work out of the path of the needle and to move the presser foot and work support out of clamping engagement with the work, and thereafter to 50 return the carriage to operating position.

6. A sewing machine having, in combination, stitch forming devices including a needle, work supporting devices including a work support and a presser foot, a carriage on which said work support and presser foot are mounted, means acting normally to hold the presser foot and work support in clamping engagement with the work, means rendered operative upon stopping the machine for actuating said carriage to move the work out of the path of the needle and thereafter to return said carriage to its operating position, and means acting prior to the return movement of said carriage to move and maintain the presser foot and work support out of clamping engagement with the work. 65 70

7. A sewing machine having, in combination, stitch forming devices including a needle, work supporting devices including a work support and a presser foot, a carriage on which said work 75

support and presser foot are mounted, means acting normally to hold the presser foot and work support in clamping engagement with the work, means rendered operative upon stopping the machine for actuating said carriage to move the work out of the path of the needle and thereafter to return the carriage to operating position, mechanism rendered operative by said outward movement of the carriage to raise and lock the presser foot out of clamping engagement with the work, and means for releasing the presser foot to clamp new work when placed in sewing position in the machine.

8. A sewing machine having, in combination, stitch forming devices including a needle, work supporting devices including a work support and a presser foot, a carriage on which, said work support and presser foot are mounted, means acting normally to hold the presser foot and work support in clamping engagement with the work, a starting and stopping treadle for the machine, means rendered operative upon releasing the treadle to stop the machine for actuating said carriage to move the work out of the path of the needle and thereafter to return the carriage to operating position, mechanism rendered operative during the outward movement of the carriage to raise the presser foot out of clamping engagement with the work, and connections controlled from said treadle in starting the machine to release the presser foot.

9. A sewing machine having, in combination, stitch forming devices including a needle, work supporting and gripping devices including a carriage, and a stop mechanism for the machine comprising means for driving the machine at relatively high and low speeds, means for advancing the carriage to move the work out of the path of the needle, and thereafter to return the carriage to operating position, and means acting during said carriage movements to drive the machine at a relatively low speed.

10. A sewing machine having, in combination, stitch forming devices including a needle, work supporting and gripping devices including a carriage, and a stop mechanism for the machine comprising means for driving the machine at relatively high and low speeds, means for advancing the carriage to move the work out of the path of the needle, and thereafter to return the carriage to operating position, and means for thereafter stopping the machine with the stitch forming devices in a predetermined position.

11. A sewing machine having, in combination, stitch forming devices including a needle, work supporting devices including a carriage, and a stop mechanism for the machine comprising means for driving the machine at relatively high and low speeds, means for advancing the carriage to move the work out of the path of the needle during the continued operation of the machine, means rendered operative during said advancing movement of the carriage to release the work, means for retarding the machine to a predetermined slow speed, means acting thereafter to return the carriage to normal operating position, and means for stopping the machine in a predetermined position with the needle retracted to permit the positioning of new work in the machine.

12. A sewing machine having, in combination, stitch forming devices including a needle, work supporting and gripping devices including a carriage, and a stop mechanism for the machine comprising means for driving the machine at

relatively high and low speeds, a starting and stopping treadle, means rendered operative upon releasing said treadle to move the work out of the path of the needle to release the work, and thereafter return the carriage to operating position, and a slow speed clutch rendered operative during said carriage movements to drive the machine at low speed.

13. A sewing machine having, in combination, stitch forming devices including a needle, work supporting and gripping devices including a carriage, and a two speed stop mechanism for the machine comprising a slow speed clutch, an auxiliary drive shaft, means rendered operative in stopping the machine to rotate said shaft through a predetermined angle, means controlled from said shaft to advance the carriage to move the work out of the path of the needle to release the work, and thereafter to return the carriage to operating position, and means controlled from said shaft to actuate said slow speed clutch to drive the machine at low speed.

14. A sewing machine having, in combination, stitch forming devices including a needle, work supporting devices including a work support and a presser foot, a feed carriage on which the work support and presser foot are mounted and a stop mechanism for the machine comprising a Geneva stop motion star wheel and connections actuated thereby for advancing the carriage to move the work out of the path of the needle and thereafter to return the carriage to operating position, and means operating on stopping the machine to impart two movements to the star wheel to move the work out of and then into the path of the needle.

15. In a sewing machine, the combination with stitch forming devices including a hook needle, of a looper, and a thread finger arranged to engage the thread between the looper and the work comprising two members movable relatively to the thread and to each other to grip and draw a bight of thread, one leg of said bight being drawn from and tightly positioned across the looper, and the other leg of said bight leading to the work containing excess thread.

16. In a sewing machine, the combination with stitch forming devices including a hook needle, of a looper, and a thread finger arranged to engage the thread between the looper and work comprising two members movable relatively to the thread and to each other to grip and draw a bight of thread, one leg of said bight being drawn from the thread supply into operative engagement with the looper in the path of the needle, and the other leg of said bight leading to the work remaining slack.

17. A sewing machine having, in combination, stitch forming devices including a needle, work supporting devices including a work support, and a presser foot, a feed carriage on which the presser foot and work support are mounted, a carrier slide to which the feed carriage is pivotally secured, means rendered operative in stopping the machine to advance the carriage slide and feed carriage to move the work out of the path of the needle, and means for moving the feed carriage laterally about its pivot to impart the required feeding movements to the work comprising a block mounted in a slot in the feed carriage with relation to which block the feed carriage moves when advanced to move the work out of the path of the needle, and means for actuating the block to swing the feed carriage about its pivot.

18. A sewing machine having, in combination, 5
stitch forming devices including a needle, work
supporting devices including a work support and
a presser foot, a feed carriage on which the
presser foot and work support are mounted, a
carrier slide to which the feed carriage is pivot-
ally secured, means rendered operative in stop-
ping the machine to advance the carrier slide
and feed carriage to move the work out of the
path of the needle, and means for moving the
feed carriage laterally about its pivot to impart
the required feeding movements to the work
comprising a block mounted in a slot in the feed
carriage with relation to which block the feed
carriage moves when advanced to move the work
out of the path of the needle, and a cam actuated
lever provided with a slot engaging the block
arranged to impart swinging movements to the
feed carriage about its pivot.
- 10 19. A sewing machine having, in combination,
stitch forming devices including a needle, work
supporting devices including a work support and
a presser foot, a feed carriage on which the
presser foot and work support are mounted, a
carrier slide to which the feed carriage is pivot-
ally secured, means rendered operative in stop-
ping the machine to advance the carrier slide
and feed carriage to move the work out of the
path of the needle, means for moving the feed
carriage laterally about its pivot to impart the
required feeding movements to the work
comprising a block mounted in a slot in the feed
carriage with relation to which block the feed
carriage moves when advanced to move the work
out of the path of the needle, and a cam actuated
lever provided with a slot engaging the block
arranged to impart swinging movements to the
feed carriage about its pivot, and means con-
veniently accessible to the operator for adjust-
ing said block to vary the extent of the feeding
movements imparted to the feed carriage.
- 15 20. A sewing machine having, in combination,

stitch forming devices including a needle and a
locking thread mechanism, work supporting de-
vices including a work support and a presser foot,
means rendered operative upon stopping the ma-
chine for actuating the work support and presser 5
foot to move the work out of the path of the
needle, a holding device for the free end of the
needle thread mounted to move bodily with the
work support and presser foot, means for actu-
ating the holding device to grip the thread dur- 10
ing the movement of the work out of the path of
the needle, a latch for retaining the holding de-
vice in gripping engagement with the thread,
and means acting, after the return of the work
support and presser foot to work receiving posi- 15
tion and during the operation of the stitch form-
ing devices in sewing a new seam, for actuating
the latch to release the thread holding device.

21. A sewing machine having, in combination, 20
stitch forming devices including a needle and a
locking thread mechanism, work supporting de-
vices including a work support and a presser foot,
means rendered operative upon stopping the ma-
chine for actuating the work support and presser 25
foot to move the work out of the path of the
needle, a holding device for the free end of the
needle thread mounted on the presser foot, a mem-
ber for actuating the holding device to grip the
thread, a yielding connection be- 30
tween said member and holding device, means for
actuating said member by the movement of
the work support and presser foot to move the
work out of the path of the needle, a latch to
engage said member to retain the holding device 35
in engagement with the thread, and means act-
ing after the return of the work support and
presser foot to work receiving position and dur-
ing the operation of the stitch forming devices in
sewing a new seam, for actuating the latch to 40
release said member.

FRED ASHWORTH.
